US00D890333S

(12) **United States Design Patent** (10) **Patent No.:** **US D890,333 S**
(45) **Date of Patent:** **** Jul. 14, 2020**

(54) **HEART VALVE DOCKING COIL**

(71) Applicant: **Edwards Lifesciences Corporation**,
Irvine, CA (US)

(72) Inventors: **Darshin S. Patel**, San Juan Capistrano,
CA (US); **Boaz Manash**, Givat Ada
(IL); **Khen Perlmutter**, Binyamina
(IL); **Noa Axelrod**, Herzeliya (IL)

(73) Assignee: **Edwards Lifesciences Corporation**,
Irvine, CA (US)

(**) Term: **15 Years**

(21) Appl. No.: **29/635,857**

(22) Filed: **Feb. 2, 2018**
